M. G. Murphy
ATTORNEY

UNITED STATES PATENT OFFICE.

MATTHEW O. COOPER, OF NEW YORK, N. Y.

QUOIN.

Application filed January 23, 1922. Serial No. 531,180.

To all whom it may concern:

Be it known that I, MATTHEW O. COOPER, a citizen of the United States, and a resident of the city of New York, borough of Queens, 5 in the county of Queens and State of New York, have invented a new and Improved Quoin, of which the following is a full, clear, and exact description.

This invention relates to improvements in 10 printers' quoins, the principal object of the invention being to provide a device of this character, comprising the usual pair of co-acting wedge members so constructed that the wedge members are positively held 15 against accidental slipping or relative movement in any direction.

A further object is to provide a quoin in 20 which the wedge members are prevented from coming apart so that there is no danger of losing one part of the quoin and no necessity for matching up the various wedge members when it becomes necessary to use a quoin.

A still further object is to provide a device of this character, which will be simple 25 and practical in construction, strong, durable and efficient in use, and comparatively inexpensive to manufacture.

With these and other objects in view, the 30 invention consists in certain novel features of construction and combinations and arrangements of parts as will be more fully hereinafter described and pointed out in the claims.

35 In the accompanying drawings:

Figure 1 is a view in side elevation of my improved quoin, parts being broken away and in section for clearness;

Figure 2 is a plan view of the wedge 40 member 2;

Figure 3 is an enlarged view in section on the line 3—3 of Figure 1;

Figure 4 is an end view of the wedge member 2; and

45 Figure 5 is a perspective view of one of the locking devices.

Referring in detail to the drawings, my improved quoin includes a pair of wedge members 1 and 2, provided with centrally 50 disposed longitudinally extending ribs 3 on their adjacent faces. The intermediate portions of the wedge members are provided at each side of the ribs with the usual rounded key-receiving teeth 4 adapted to receive a 55 conventional type of key to effect relative

longitudinal movement of the wedges. Rails 5 are secured upon the meeting faces of the ribs 3.

The rails 5 are slightly wider than the ribs to which they are attached by suitable securing devices, such as 6, and the edges of the rails which extend beyond the edges of the ribs are corrugated or toothed, as indicated at 7, for a purpose which will hereinafter appear. 60

The head 8 of each wedge is formed with a pair of extensions 9 straddling the rails 5 and with inwardly presented lugs 10 overlying the rails and spaced a sufficient distance apart to conveniently accommodate the 70 ribs 3. The lugs 10 serve to positively prevent relative separation of the wedge members.

It has been heretofore noted that the principal object of the invention was to provide 75 means for preventing accidental longitudinal movement of the wedges relative to each other. With this end in view, a pair of substantially U-shaped members 11 are provided. These members are secured in the heads 8 of the wedges, the intermediate portions of the members being secured to the ends of the ribs 3 and being recessed, as indicated at 12. The recesses 13 in the intermediate portions of the members 11 serve to accommodate the rails 5 of the opposite wedge members. The U-shaped locking members 11 each include a pair of corrugated spring arms 14 extending inwardly from the heads 90 of the wedges and embracing the rails 5. 80

It is of course to be understood that the corrugated arms 14 are shaped in accordance with the corrugations or teeth 7 of the rails. The arms are pressed by their own resiliency into embracing relationship with the two 95 rails and serve to positively prevent accidental longitudinal movement of the wedges relative to each other. The spring arms 14 do not hold the wedge members against movement when a key is inserted to actuate 100 the same, but are sufficiently strong to retard the movement of the wedges when a key is applied and to absolutely prevent accidental movement thereof.

A pin 15 carried by one of the ribs 3, is 105 engageable with the extensions 9 of the head of the opposite wedge member to limit longitudinal movement of the members in one direction and the two heads engage each other to limit longitudinal movement in the 110

other direction. Relative separation of the wedges is prevented in the manner hereinbefore described.

I prefer to make the wedge members of 5 malleable iron, the rails of case hardened steel and the locking members of spring steel, but the material from which the wedges are made, can of course, be varied to suit the trade.

10 Although I have illustrated one of the preferred embodiments of my invention, it will be apparent that various slight changes and alterations might be made in the general form and arrangement of the parts described without departing from the invention, and hence I do not wish to limit myself to the precise details set forth, but shall consider myself at liberty to make such slight changes and alterations as fairly fall within 15 the spirit and scope of the appended claims.

I claim:

1. In a quoin, a pair of coacting wedge members, longitudinal ribs on the members engaging rails mounted on the ribs, and 25 means engageable with the rails preventing accidental longitudinal movement of said members, said rails including corrugated edges projecting beyond the edges of the ribs, said means comprising spring arms engageable with the edges of the rails.

2. In a quoin, a pair of coacting wedge members, longitudinal ribs on the members engaging rails mounted on the ribs, and 35 means engageable with the rails preventing accidental longitudinal movement of said members, said rails including corrugated edges projecting beyond the edges of the ribs, said means comprising spring arms engageable with the edges of the rails, and 40 said arms being corrugated in conformity with the corrugated edges of the rails.

3. A quoin comprising a pair of coacting wedge members, longitudinal ribs on the

members, rails mounted on the meeting faces of the ribs and extending beyond the edges 45 of the ribs, and heads on the wedges including means engaging the rails to prevent relative separation of the wedge members.

4. A quoin comprising a pair of coacting wedge members, longitudinal ribs on the members, rails mounted on the meeting faces of the ribs and extending beyond the edges of the ribs, heads on the wedges including means engaging the rails to prevent relative separation of the wedge members, and means 55 holding the wedges against accidental relative longitudinal movement.

5. A quoin comprising a pair of coacting wedge members, longitudinal ribs on the members, rails mounted on the meeting faces 60 of the ribs and extending beyond the edges of the ribs, heads on the wedges including means engaging the rails to prevent relative separation of the wedge members, and means holding the wedges against accidental relative longitudinal movement, said means 65 comprising U-shaped members fixed at their intermediate portions to the ends of the ribs, and including spring arms straddling and engaging the rails. 70

6. A quoin comprising a pair of coacting wedge members, longitudinal ribs on the members, rails mounted on the meeting faces of the ribs and extending beyond the edges 75 of the ribs, heads on the wedges including means engaging the rails to prevent relative separation of the wedge members, and means holding the wedges against accidental relative longitudinal movement, said means comprising U-shaped members fixed at their 80 intermediate portions to the ends of the ribs, and including spring arms straddling and engaging the rails, and similar corrugations on the rails and arms aiding the holding action of the arms.

MATTHEW O. COOPER.
